UNITED STATES PATENT OFFICE

JOHN S. RICE, OF BIGLERVILLE, PENNSYLVANIA, ASSIGNOR TO RICE, TREW & RICE CO., INC., OF BIGLERVILLE, PENNSYLVANIA, A CORPORATION OF PENNSYLVANIA

BASKET LINER

Application filed April 11, 1929. Serial No. 354,366.

This invention relates to basket liners and it is an object of the invention to provide a liner of this kind particularly adapted for use with baskets adapted to be filled with 5 fruit and the like and which provides an effective means to protect the content of the basket from injury by coming in contact with the wall proper of the basket.

It is also an object of the invention to provide a liner of this kind of a split type having 10 means for connecting the free end portions thereof so that the liner will hold a column of fruit and the like without any independent support and before being applied within a 15 basket.

An additional object of the invention is to provide a liner of this kind initially of a split type and having associated therewith means for connecting the free end portions of the 20 liner, said connecting means being such to permit relative slippage of said free end portions to assure the proper fitting of the liner within a tub, and to allow the filled liner, after the tub is removed, to accommodate itself to the size of the basket applied thereover, thus assuring proper filling of the 25 basket and substantially eliminating injury to the liner.

A still further object of the invention is to 30 provide a liner formed of relatively strong material and also to provide a liner normally of a split type and having a member for connecting the free end portions of the liner, said member being of a length to project beyond the upper marginal portion of the liner 35 when applied within a basket to facilitate the removal of said member and also to provide a hinderance or obstruction to the proper application of the basket lid whereby effective 40 warning may be given to the packer that said member has not been removed.

The invention consists of the details of construction and in the combination and arrangement of the several parts of my improved basket liner whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying 55 drawings, wherein:—

Figure 1 is a vertical sectional view illustrating a liner constructed in accordance with an embodiment of my invention as initially used in connection with a packing operation; 60

Figure 2 is a view partly in section and partly in elevation showing the liner in the step of packing wherein said liner supports its content in column without independent support, a basket being diagrammatically 65 indicated by broken lines in partly applied position;

Figure 3 is a view partly in elevation and partly in section illustrating a basket in proper upended position with the coupling 70 member of the lines projecting above the liner offering hinderance to the proper application of the basket lid;

Figure 4 is a view in perspective of my improved liner as herein disclosed with its 75 free end portions connected;

Figure 5 is a fragmentary sectional view taken substantially on the line 5—5 of Figure 4;

Figure 6 is a view in plan of one of my 80 improved liners in blank form.

Figure 7 is a fragmentary view in perspective of the liner illustrating with greater clarity the direction of the grain of the 85 stock.

My improved liner L as herein embodied comprises a sheet of material, such as cardboard or the like, which possesses sufficient strength as to substantially eliminate breakage of the liner when applied within a 90 basket as a result of the pressure imposed thereon by the weight of the basket content, such as apples and the like. The liner L is formed from a paper stock wherein the grain α is disposed in a general direction lengthwise of the liner thus assuring the liner affording a strong wall not liable to breakage. This disposition of the grain also causes the liner to have a natural tendency 95 to readily open or spread out, thus facilitat- 100

ing the application of the liner in working position.

The liner, as illustrated in Figure 6, is initially of a split form and in blank comprises an elongated sheet disposed lengthwise upon a desired curvature and which is provided at desired points thereon with the openings 1 to assure desired circulation of air through the completed package to offset deterioration of the basket content.

The liner L in its initial or blank form has its curvature arranged on a radius determined by the size of the shell or tub S in which it is to be applied. When the end 15 portions of the liner are in overlapping relation the liner will substantiate a truncated cone to approach the internal contour of the side wall of the shell or tub S with which the liner, when applied, is adapted to have 20 close contact.

The liner L in each end portion thereof is provided with a plurality of openings 2 substantially in radial alignment, said openings preferably constituting slots having their longitudinal axes disposed lengthwise of the blank as illustrated in Figure 6 or circumferentially of the liner when in applied position. The openings or slots 2 at each end portion of the liner L are so positioned that when the end portions of the liner are in overlapping relation the openings or slots 2 at one portion will register with the openings 2 at the other end portion.

When the end portions of the liner L are in overlapping relation, the liner will simulate a continuous wall and will be in proper formation as illustrated in Figures 2 and 4 for use in the desired packing operations.

40 The end portions of the liner L are maintained temporarily in desired overlapping relation through the medium of an elongated member 3 of any desired material. This member 3 is of a length materially in excess of the width of the liner when in blank so 45 that when in applied position an end portion of the member 3 will project beyond an open end of the assembled liner.

50 My improved liner is particularly adapted for use in connection with a well known method of packing fruit and the like employing a facing form F and shell or tub S although my improved liner can be employed under certain conditions independently of the shell. As herein embodied, after a layer 55 of fruit has been properly positioned upon a facing form F a shell or tub S with an applied liner L is placed thereon. The applied liner and shell are then filled with fruit, as indicated in Figure 1. After this filling operation with the shell or tub S is removed leaving the liner L holding the fruit or kindred content in column free of any independent support. An inverted basket B is 60 then applied over said liner L, as indicated by broken lines in Figure 2. It is to be noted

that when the shell or tub S and liner L are applied upon the facing form F, the connecting or coupling member 3 will project above the top thereof. As the basket B is forced over the filled liner the bottom of the basket will come in contact with this extended end of the member 3 so that when the basket and liner with its load is up-ended, the member 3 will project above the top of the basket and thereby provide means whereby the member 3 may be readily removed by the packer before the basket top or lid T is applied. In the event the packer should fail to remove the member 3, the upper projecting portion thereof, as indicated in Figure 3, will offer hindrance or obstruction to the proper application of the top or lid T thus necessitating the packer removing the member 3 before the top or lid T can be properly applied.

With the member 3 removed it will be readily understood that the liner L is of a split type thereby assuring the proper expanding of the liner L if required within the basket as the fruit or other content is shaken down therein. By this the basket B may be properly filled. 85 96

It is also to be stated that before the member 3 is removed the registering openings or slots 2 will permit relative slippage between the overlapping end portions of the liner L so that initially the liner L can effectively adjust itself for proper fitting within the shell or tub S, thus materially facilitating the packing operation. This adjustment of the liner L also allows contraction and expansion of the filled liner to accommodate it to the size of the basket applied thereover after the tub has been removed. 95 10.

This application is partly in continuation of application Serial No. 350,817 filed March 27, 1929, and this application contains subject-matter claimed in my pending application filed October 2, 1929. 103

From the foregoing description it is 111.
thought to be obvious that a basket liner con-
structed in accordance with my invention is
particularly well adapted for use by reason of
the convenience and facility with which it
may be assembled and employed, and it will
also be obvious that my invention is suscepti-
ble of some change and modification without
departing from the principles and spirit
thereof and for this reason I do not wish to
be understood as limiting myself to the pre-
cise arrangement and formation of the several
parts herein shown in carrying out my invention
in practice except as hereinafter claimed. 120

I claim:—

1. As a new article of manufacture, a split basket liner for use in packing fruit and the like having a plurality of openings in its end portions, the openings in one end portion registering with the openings in the other end portion when said end portions are in over- 120

lapping relation, and a substantially rigid member threading through said openings, said openings and substantially rigid member being so proportioned to provide a degree of adjustability in assembling the basket over the filled liner and permitting the liner to accommodate itself to the content and basket.

2. As a new article of manufacture, a split basket liner for use in packing fruit and the like having a plurality of openings in its end portions, the openings in one end portion registering with the openings in the other end portion when said end portions are in overlapping relation, and a substantially rigid member threading through said openings, said openings and substantially rigid member being so proportioned as to provide a degree of adjustability in assembling the basket over the filled liner and permitting the liner to accommodate itself to the content and basket, said substantially rigid member being of a length to extend beyond a margin of the liner to facilitate removal of said member.

3. As a new article of manufacture, a split basket liner for use in packing fruit and the like having a plurality of openings in its end portions, the openings in one end portion registering with the openings in the other end portion when said end portions are in overlapping relation, and a substantially rigid member threading through said openings, said openings and substantially rigid member being so proportioned to provide a degree of adjustability when the liner is applied within a tub whereby expansion and contraction of said liner is allowed to accommodate it to the size of the tub.

4. As a new article of manufacture, a split packing liner for use in packing fruit and the like, comprising a strip of lining material having perforated ends, and a fastener passing through the ends and securing them together in overlapping relation, said ends providing fastener receiving registration of perforations when the ends are overlapped by different amounts whereby adjustment of the size of the liner may be secured in the application of the liner within a tub to accommodate the liner to the size of the tub, said fastener serving to maintain the filled liner in shape after the tub has been removed.

5. As a new article of manufacture, a split packing liner for use in packing fruit and the like, comprising a strip of lining material having a plurality of perforations in each end, and an elongated pin passing through the ends a plurality of times and securing them together in overlapping relation, the ends providing pin receiving registration of perforations when the ends are overlapped by different amounts whereby adjustment of the size of the liner may be secured in the application of the liner within a tub to accommodate the liner to the size of the tub, said

pin serving to maintain the filled liner in shape after the tub has been removed.

6. As a new article of manufacture, a packing liner for use in packing fruit and the like having a removable rod coacting with portions of the liner to hold the same against expansion, the liner, when said rod is removed, being so constructed as to provide expansion of the liner, said rod being of a length greater than the distance between the opposite ends of the liner when within the container thereby permitting the removal of the rod to be effected when the liner is full without disturbance of the content therein and assuring the desired effective placement of the rod by contact of the rod with a wall of the container in which the liner is applied.

In testimony whereof I hereunto affix my signature.
